UNITED STATES PATENT OFFICE.

HARRY C. HOCHSTADTER, OF PHILADELPHIA, PENNSYLVANIA.

DENTAL FLOSS HOLDER.

Application filed March 19, 1925. Serial No. 16,601.

This invention, generally stated, relates to containers and has more especial relation to a holder for receiving and maintaining in a sanitary condition dental floss.

The leading object of the present invention may be said to reside in a holder of the character stated in which desired lengths of dental floss may be withdrawn from the holder without exposing the main supply of material.

A further object of the present invention resides in the provision of means whereby that portion of the dental floss being fed forwardly may be interlocked with respect to the neck of the holder when desired. Other and further objects of the present invention reside in the provision of general details of construction and arrangement of parts for attaining the results sought by the above objects. Other and further objects not at this time appearing will be herein-after referred to.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in perspective of a dental floss holder embodying features of the invention.

Fig. 2, is a view in longitudinal section taken upon the line 2—2 of Fig. 1.

Fig. 3, is a view in cross section taken upon the line 3—3 of Fig. 2.

Fig. 4, is a view in cross section taken upon the line 4—4 of Fig. 2; and

Fig. 5, is a view in cross section taken upon the line 5—5 of Fig. 2.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail the reference numeral 1 designates a receptacle for containing a roll of dental floss 2. In

practice the receptacle 1 is made of glass although obviously other material may be employed if desired. The open end or neck of the receptacle 1 is designated 3 and in the present instance is shown as being screw-threaded for the removable reception of a cap 4, preferably of metal, and interiorly screw-threaded for cooperation with the exteriorly screw-threaded neck 3 of receptacle 65

1. The outer end of cap 4 is provided with a socket 5 the inner wall 6 of which socket is apertured as at 7. Arranged in the space within the cap and between the wall 6 and the outer circumference of the receptacle 70 neck are a plurality of discs, two of which are shown, and which are designated 8 and 9, and at least one of which, preferably that designated 9, is apertured as at 10. These discs may be of hard fibre or other suitable 75 material. These discs are of a diameter so as to more or less snugly engage the inner wall of cap 4, as clearly illustrated in Fig. 2. Fitted to socket of cap 4 is a conical shaped tip 11 preferably of relatively soft rubber so 80 as not to injure the mouth of the user. The tip has extended therethrough a longitudinal passage 12 in register with the aperture 7 of the inner wall 6 to cap 5, best seen in Fig. 2. The cap 5 preferably has secured adjacent its outer end a cutting device 13 whereby the used end of a strand of dental floss may be cut off after use.

In use a loose end of the dental floss is passed between the inner wall of cap 4 and 90 the circumferential edge of disc 8, thence upwardly and downwardly through aperture 10 of disc 9 and thereafter downwardly and outwardly through aperture 7 in wall 6 and passage 12 as clearly illustrated in Fig. 2. 95 With the cap 4 screwed down tightly to place, as shown in Fig. 2, the strand of dental floss is firmly clamped between the inner wall of cap 4 and the circumferential edge of disc 8. In this position the strand 100 of dental floss is positively locked with respect to cap 4 and no dental floss can be pulled through tip 11. However, upon loosening of cap 4 with respect to the neck of receptacle 1 the user by pulling upon the 105 end 14 of the strand of dental floss can secure the amount desired because pull exerted upon the end 14 of the dental floss causes disc 8 to sufficiently tilt to remove the tension previously exerted upon the strand of 110 dental floss as is readily apparent.

It will now be apparent that I have de-

vised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. An article of the character stated, comprising a receptacle for containing dental floss, a closure adjustably secured upon the neck of said receptacle, said closure having an apertured socket therein, a pair of discs one of which is apertured, arranged between the neck of the receptacle and said socket, an apertured conical tip fitted to said socket and dental floss contained within said receptacle having a strand thereof passed between a disc edge and said receptacle neck, thence through the aperture of a disc and finally out through said tip, whereby proper adjustment of said closure results in tension being removed from said strand of dental floss.

2. An article of the character stated, comprising a receptacle the neck of which is shaped to receive a closure, a closure consisting of a cap removably fitted to the neck of said receptacle, said cap having an aper-

tured socket, a plurality of discs arranged within said cap between the receptacle neck and said socket, at least one of said discs being apertured, and a conical tip fitted to said socket and having a passage therethrough in register with the socket aperture.

3. An article of the character stated, comprising a receptacle the neck of which is shaped to receive a closure, a closure consisting of a cap removably fitted to the neck of said receptacle, said cap having an apertured socket, a plurality of discs arranged within said cap between the receptacle neck and said socket, at least one of said discs being apertured, a conical tip fitted to said socket and having a passage therethrough in register with the socket aperture, and a cutter arranged at the forward end of said cap.

4. An article of the character stated comprising a receptacle of transparent material, the neck of which is shaped to receive a closure, a closure of thin metal removably secured to said receptacle, said closure having an apertured socket, a tip of relatively pliable material having a passage therethrough fitted to said socket, a pair of washers one of which is apertured, arranged between said receptacle end and said socket, and dental floss within said receptacle a strand of which is threaded between the inner wall of said cap and the circumferential edge of a washer and through another washer and thence through said tip.

In testimony whereof, I have hereunto signed my name.

HARRY C. HOCHSTADTER.
